UNITED STATES PATENT OFFICE.

WILLIAM G. MERCER, OF BURLINGTON, IOWA.

HUB FOR VEHICLE-WHEELS.

SPECIFICATION forming part of Letters Patent No. 329,061, dated October 27, 1885.

Application filed January 16, 1885. Serial No. 153,104. (Model.)

To all whom it may concern:

Be it known that I, WILLIAM G. MERCER, a citizen of the United States, residing at Burlington, in the county of Des Moines and State 5 of Iowa, have invented a new and useful Improvement in Hubs for Vehicle-Wheels, of which the following is a specification.

This invention relates to vehicle-wheel hubs; and it consists in the construction hereinafter 10 pointed out.

In the annexed drawings, Figure 1 is a view of a wooden hub to which my invention is applied; Fig. 2, a side view, partly broken away, of the sleeve.

15 The letter A indicates a wooden hub having the cylindrical end a , conical bearing a' , and the approximately-cylindrical spoke portion a'' . On this hub is to be placed the sleeve B. This sleeve has the portions e , f , and c to correspond with portions a , a' , and a'' of the hub 20 A. Portion e is continued into the point-band b , and portion c into the flange c' .

On the inner face of the conical portion f of the sleeve B are corrugations b' , terminating at $b^2 b^3$, and made integral with such sleeve. 25 When the latter is placed upon the wooden hub, these corrugations do not enter endwise into the wood; but as the sleeve comes down on the wood such corrugations press with their edges into the latter. 30

I am aware that hub-bands have had ribs on cylindrical portions of their length.

What I claim is—

The hub A, having the cylindrical portions a and a' and conical portion a' , in combination 35 with the sleeve B, having cylindrical portions b and c and conical portion f , the latter having corrugations on its inner face, as set forth.

WILLIAM G. MERCER.
